CARRYING HANDLE FOR SKIS AND SKI POLES

Ronald R. Klawitter, 524 E. Cedar St., Burbank, Calif.
91501, and Cleve A. Graham, 309 2nd St., Port
Hueneme, Calif. 93041

Filed Mar. 24, 1975, Ser. No. 561,596

Term of patent 14 years

Int. Cl. D3—02

U.S. Cl. D87—1 R

FIG. 1

FIG. 4

FIG. 2

FIG. 5

FIG. 6

FIG. 1 is a perspective view of a carrying handle for skis and ski poles showing our new design;
FIG. 2 is a reduced scale top plan view;
FIG. 3 is a bottom plan view thereof;
FIG. 4 is an end elevational view thereof;
FIG. 5 is a rear elevational view; and
FIG. 6 is an enlarged scale cross-sectional view taken along line 6—6 of FIG. 1.

We claim:

The ornamental design for a carrying handle for skis and ski poles, as shown and described.
